CLARENCE E. ANABLE, OF SACRAMENTO, CALIFORNIA.

PERMUTATION-LOCK.

1,312,938.

Specification of Letters Patent.

Patented Aug. 12, 1919.

Application filed February 14, 1918. Serial No. 217,102.

To all whom it may concern:

Be it known that I, CLARENCE E. ANABLE, a citizen of the United States, residing at Sacramento, in the county of Sacramento 5 and State of California, have invented certain new and useful Improvements in Permutation-Locks, of which the following is a specification.

By this invention a simple permutation 10 lock is produced wherein the operating spindle serves as the locking bolt or itself locks such bolt.

With this operating spindle are associated 15 in an effective way indicating mechanism whereby, in the manipulation of the lock, the combination may be followed by sight, sound or feeling.

The structure and association of parts 20 are also such that the number of combinations to which the lock may be set is practically unlimited.

The invention therefore consists in the 25 structure of parts and in their combination for the purpose specified substantially as herein set forth and claimed.

In the drawings which form a part of this 30 specification, Figure 1 represents in plan the improved lock applied to the steering post of an automobile. Fig. 2 is a vertical section of the lock on line 2—2, Fig. 1, some parts being shown in elevation. Fig. 3 is a 35 plan of the upper part of the casing detached. Fig. 4 is a transverse section on line 4—4, Fig. 3. Fig. 5 is a plan of the ratchet portion of the "click" mechanism. Fig. 6 40 is an underside view of the concentric tumblers. Fig. 7 is a transverse section on line 7—7, Fig. 6. Fig. 8 shows the lock in side elevation applied to the bolt of a safe door.

The chief element of the lock—the spindle—is indicated by 10. This is mounted 45 in a casing made in any suitable way but here shown of two parts, the base 11 for attachment to the structure to be locked and the cap 12 fitting over the base and held 50 in place by a screw 13. The steering post of an automobile is indicated at 14 and to this the base of the lock may be secured in any safe way as by strap 15 and rivets 16.

The spindle 10 is axially located in the casing for rotation and reciprocation. The lower edge or shoulder 17 of the head or knob on the spindle is preferably located 55 in a recess in cap 12 sufficiently deep to prevent the insertion of a prying tool under the knob. The floor of said recess constitutes a

flange or ledge 18 and in this ledge is a notch 19, at either side of which are guard recesses 20 to receive restraining pin 21 should the spindle accidentally turn while 60 in unlocked position. When the knob and spindle are made separately the pin 21 may also secure these parts together.

The tumblers consist of concentrically located rings 22 and 23. More may be used 65 if desired to multiply the combinations. Tumbler 22 is preferably provided with a flange to be seated in a recess in the top of the outer tumbler 23 so that they may be retained in the same plane. A spring 24 70 supports the tumbler 23, itself being supported, where need be, by a washer 25 resting on the curved surface of the steering post. When the lock is designed for attachment to a flat surface, as in Fig. 8, this 75 washer may be omitted. The tumblers are provided with pins 26, 27 and 28, 29 with which the operating arm 30, projecting from the spindle, may engage to move the tumblers. 80

Upon the base 11, surrounding the spindle 10, is the ratchet member 31 of a "click" mechanism. A finger 32 projects from the spindle for engagement with the ratchet. Above the finger 32 is a washer 33 and between this and the top of cap 12 is placed 85 a spiral spring 34 which serves to press the finger into the notches of the ratchet and to enter the spindle into the locking socket. The head of the spindle, or knob 100, is 90 suitably milled to provide a gripping surface to assist in the manipulation of the lock.

In the drawings the spindle is shown in locking position. To unlock the steering 95 gear the spindle must be lifted out of the socket in the steering shaft 35. Such axial movement of the spindle can be effected only when restraining pin 21 is in line with the notch 19. At the same time the tumblers 100 must be in a certain definite position to provide, by means of channels therein, a passage for the arm 30. Such channels or recesses are indicated at 36 and 37, Figs. 6 and 7. The channel 36 does not extend clear 105 across ring 23 and therefore does not interrupt the bearing surface for spring 24.

The lock is manipulated as follows:

Supposing it to have been set for the combination "5 left 3 right" and that the 110 starting point, and therefore the stopping point, is 00 on the dial, which with respect

to touch and sound means the smooth space 38 on the ratchet. Following the dial and starting with the arrow head 39, on the knob, at 00, the knob is turned to 5 during 5 which movement finger 30 engages pin 26 and turns tumbler 23 so as to place recess 36 under 00. Then by reversing and turning the arrow head to 23 on the dial, the finger engages pin 28 and turns tumbler 22 so as to 10 place recess 37 under 00 and in alinement with recess 36. Then on turning the arrow head back to 00, the arm 30 can be lifted into the alined recesses, and the spindle withdrawn from the socket in the steering shaft. To hold the spindle out of said 15 socket, the knob may be turned to right or left so that the restraining pin 21 may rest upon the ledge 18 until the lock is to be again applied. A safeguard against accidental 20 operation of the lock, due to rotation of the spindle by car vibration or otherwise, is provided by the pockets 20 at either side of notch 19 into which pockets pin 21 would drop and be held instead of passing down 25 through notch 19 and thereby allowing the lower end of the spindle to enter one of the locking sockets in the steering shaft when brought under it in directing the car.

The lock is operated by simply lifting the 30 knob 100, enough to raise pin 21 out of a pocket 20, turning the arrow head to 00 and letting go of the knob. Pin 21 then passes through notch 19 and the spring 34 forces the end of the spindle into a locking socket. 35 Three radial locking sockets are shown in the steering shaft whereby said shaft may be locked, as in Fig. 2, with the directing wheels straight ahead. The directing wheels may be locked to the right by using socket 40 or to the left by using socket 41. The spindle 40 is then turned to upset the combination.

The ratchet or click mechanism has its notches arranged to correspond to the graduations of the dial. It is therefore useful in 45 working out a combination by the dial since it halts the arrow head definitely at the graduations. Said mechanism however has a more useful function. It renders possible the operation of the combinations of the lock 50 without the aid of the dial and even without any dial, since the stepping of the finger from notch to notch can be heard and also felt, thereby rendering the lock easily operable in the dark.

55 The zero, or the blank space 38, constitutes the usual starting point for a combination, as in the manipulation of the lock recited. Any number however on the dial, or any notch of the ratchet, may be taken as 60 the starting point in operating a selected combination for which the lock has been set. For example take 6 as the starting point for the combination "left 3 right 2." The operator rotates the knob till finger 32 slides 65 on smooth space 38, or the arrow head is at

00, then he counts around to 6, moves three steps to the left of that then back to 6 and two steps to the right of that. He may then turn the knob back to 00, or the finger to smooth space 38, and raise the spindle, the 70 arm 30 entering the alined recesses 36, 37, in the tumblers and the restraining pin 21 passing through notch 19 to rest on ledge 18 as the knob is given the final twist to right or left to hold the spindle in unlocked position. 75

The combinations of a lock provided with a dial may be varied by removing screw 13 and rotating cap 12 to another position on the base, a succession of screw holes 45 being 80 provided in the base for the screw 13. By providing screw sockets 46 and 47 in the respective tumblers, the screw pins 26, 27, 28 and 29 may be shifted through a still wider range of combinations. 85

The lock of this invention is adaptable to universal use, other instances of its use, aside from the one above described, being typified in Fig. 8. Therein the spindle locks a sliding bolt, as 42, of a safe door 43, the handle 90 44 serving to throw back said bolt in the usual way in the act of unlocking the door. Thus the spindle may lock a locking bolt or as in the first instance it may itself serve as the locking bolt. 95

The invention claimed is:—

1. The combination of a rotary and axially movable spindle; combination tumblers actuated by the spindle and comprising concentric, rotatable rings each having a radial opening; an arm carried by the spindle adapted to enter said openings when the latter are in alinement; a pin projecting from the spindle; a casing having a cap member through which the spindle passes, said cap member having a notch through which said pin may pass, forming a fixed tumbler; an operating piece carried by said spindle extending over and adapted to conceal said notch; and a part to be locked by said spindle. 100

2. The combination of a rotary and axially movable spindle; combination tumblers actuated by the spindle and comprising concentric rotatable rings each having a radial opening; an arm carried by the spindle adapted to enter said openings when the latter are in alinement; a pin projecting from the spindle; a casing having a cap member through which the spindle passes, said cap member having a sunken flange provided with a notch through which said pin may pass, said flange forming a fixed tumbler; a knob carried by said spindle; and adapted to cover and conceal said notch, and a part to be locked by said spindle. 115

3. The combination of a rotary and axially movable spindle; combination tumblers actuated by the spindle and comprising concentric rotatable rings each having a radial 120

opening; an arm carried by the spindle adapted to enter said openings when the latter are in alinement; a pin projecting from the spindle; a casing comprising a pair of 5 tubular members one fitting into the other, one of said members serving as a cap for the other member and having a depressed outer portion, said depressed portion being provided with a notch through which said pin

may pass, said spindle having an actuating 10 knob fitting the depression in the cap member and extending over and concealing said notch; and a part to be locked by said spindle.

In testimony whereof I have affixed my 15 signature.

CLARENCE E. ANABLE.
